ATTORNEY

UNITED STATES PATENT OFFICE.

FRANK A. FREEMAN, OF PHILADELPHIA, PENNSYLVANIA.

DESIGN FOR A BUCKLE-PIECE.

SPECIFICATION forming part of Design No. 34,992, dated August 27, 1901.

Application filed July 29, 1901. Serial No. 70,191. Term of patent 14 years.

To all whom it may concern:

Be it known that I, FRANK A. FREEMAN, of the city of Philadelphia, county of Philadelphia, and State of Pennsylvania, have invented and produced a new and original Design for a Buckle-Piece, of which the following is a specification.

In the accompanying drawings, Figure 1 is a front elevation of said buckle-piece, and Fig. 2 is a side view of same.

The leading and characteristic features of my design are a strap or outer member 1, having its upper overlapping portion 2 passed through a slotted plate 3, another strap or member 4 extending longitudinally along the outer member 1 and within its margins, said

inner strap or member 4 having segmental recesses 5 on either side of its two extremities, making said extremities narrower than the middle or intermediate portion of said inner member 4, a circular ornamentation 6 upon the overlapping portion 2, and a circular ornamentation 7 upon the lower extension of inner member 4.

I claim—

The design for a buckle-piece substantially as herein shown and described.

FRANK A. FREEMAN.
